ELECTRICAL COIL AND A METHOD OF
MAKING SUCHRaymond E. Powell, Westfield, N. J., assignor to
Western Electric Company, Incorporated, New
York, N. Y., a corporation of New York

Application January 11, 1945, Serial No. 572,354

8 Claims. (Cl. 219—13)

1

This invention relates to an electrical coil and a method of making such, and more particularly to an electrical coil for heating articles in the field generated thereby and having means to circulate a cooling fluid through the substance of the coil and to a method of making such a coil.

Electrical coils to conduct current in a helical path about a space wherein an alternating electric field is to be generated to heat articles introduced into the space have long been used in variously constructed heating devices, ovens, furnaces and the like. In one distinct class of such coils, heat is not generated in the substance of the coil itself, but is generated by conversion of the electrical energy of the field into heat energy within an article immersed in the field of the coil. In such a coil it is undesirable that the temperature of the conductor of the coil be raised by heat derived by radiation or conduction from the heated article. Hence such coils may be constructed to have or be provided with passage ways within or associated closely with the conductor elements for the circulation of fluid media to keep the conductors cool. The conductive element of such a coil is frequently made by bending a tube of suitable electrically conductive metal, e. g., copper, silver, aluminum, or other suitably conductive and ductile metal or alloy of such. The substance of the tube is then the electrical conductor of the coil and the cooling fluid may be circulated within the tube as necessary. Coils so constructed may be eminently satisfactory for some such uses, but are affected with material drawbacks in some instances. It is difficult to bend the tube from which the coil is made to the relatively small radius of the helical form desired without either forming folds in the inner side of the curvature, which may obstruct the passage-way within, or cracking or rupturing the over-stretched substance of the tube wall at the outer side of the curvature, especially when a large cross-sectioned mass of metal is desired to carry a relatively heavy current.

An object of the present invention is to provide a simple method of making from suitably conductive material, which need not necessarily be ductile, an electrical coil to carry a heavy current in a helical path about a chamber for heating articles and having passageways within the substance of the conductor thereof for the circulation of a cooling fluid.

Another object of the invention is to provide a coil of the character described which is simple in construction and durable and efficient in op-

eration, the substance of which need not necessarily be ductile.

With the above and other objects in view, the invention may be embodied in the method of making an integral angularly helical electrically conductive member which method comprises steps of forming a chamber in a body of electrically conductive material, and forming three plane slots in the body all intersecting the chamber and no two slots being parallel or co-planar, the three slots and the chamber being so disposed and proportioned that the substance of the body is thereby divided into integrally united segments in an angularly helically aligned sequence coiled about the chamber.

Other objects and features of the invention will appear from the following detailed description of an embodiment thereof, taken in connection with the accompanying drawings, in which the same reference numerals are applied to identical parts in the several figures, and in which

Fig. 1 is a view in front elevation with parts broken away of a coil constructed in accordance with the invention;

Fig. 2 is a plan view thereof with parts broken away;

Fig. 3 is a view on the line 3—3 of Fig. 2;

Fig. 4 is a view on the line 4—4 of Fig. 2; and

Fig. 5 is a schematic view thereof in perspective from the rear to show the current and circulatory paths.

The coil herein disclosed as an illustrative embodiment of the invention is a duplex heating coil having two chambers 10 and 11 into which articles to be heated may be inserted. The single integral body 12 of the twin helical coils was originally a solid rectangularly parallelopipedal block of copper or graphite or other suitable electrically conductive material. As hereinafter explained, the material of the coil is not necessarily restricted to be ductile, since the coil is created from such a solid block without any bending or otherwise deforming operation.

A suitably dimensioned block of the material selected has bores drilled therein as shown. A vertical bore 14 is drilled near and parallel to both the rear and right end faces of the block opening from the top face and extending down nearly to, but not through the bottom face. The bore 14 is counterbored as at 15 in its upper portion to receive a metal tube 16 conductively secured therein. A horizontal bore 17 is drilled in from the right end face near and parallel to the rear and bottom faces of the block, intersecting the bore 14 at its bottom, and extending leftwardly

to within a small distance short of the midlength of the block. The outer end of the bore 17 is counterbored a short distance to receive a closure cap 18 secured therein by any suitable means such as press fitting, soldering or screw threaded engagement. A bore 19 is drilled from the top surface vertically down near and parallel to the rear wall, a little to the right of the midlength of the block, down near to, but not through the bottom face of the block, and intersecting the bore 17 at the inner end thereof. The outer end of the bore 19 is closed with a cap 20. From the rear face of the block near and parallel to the top face, parallel to the right end face, and near the midlength of the block, a bore 21 is drilled horizontally forward toward, but not through the front face of the block, intersecting the bore 19 near its upper end, and is closed with a cap 22. From the right end face of the block, a bore 23 is drilled horizontally near and parallel to the top and front faces of the block, ending near and short of the midlength of the block and intersecting the bore 21, the outer end of the bore 23 being capped at 24. A vertical bore 25, capped at 26, intersects the bore 23 near the right end of the latter and extends downwardly, near and parallel to the right end face and the front end of the front face of the block, nearly down to, but not through the bottom face of the block. A horizontal bore 27, capped at 28, extends from the right end face of the block near and parallel to the front and bottom faces of the block and intersecting the bore 25 nearly to, but not through the left end face of the block.

If the bores 14, 17, 19, 21, 23, 25 and 27 be traced out in succession, it will be found that they form a continuous, rectangularly helical passageway of one and a quarter turns lying wholly within the right hand half of the body 11. The chamber 11 is a horizontal bore drilled through the block from front to back with its axis in the axis of the helical passageway.

A slot 30 is cut in the body of the block transversely across the block at its midlength from the top down to about the middle and from the rear face forward to about the middle leaving the right and left hand halves of the block integrally connected, as best shown in Fig. 4, over only the lower front quarter of the vertical central front to back cross section. A parallel slot 31, midway between the slot 30 and the right end face of the block extends downwardly from the top face of the block into the chamber 11 over the rear half of the front to back dimension of the block. A slot 32 parallel to the front and rear vertical faces of the block and midway between them divides the front half of the right half of the block from the corresponding rear portion over all but the left upper quarter thereof as best shown in Fig. 3. A horizontal slot 33 extends from the chamber 10 to the chamber 11 and half way back through the block from the front face.

If now the one and a quarter turn helical passageway of the bores 14, 17, 19, 21, 23, 25 and 27 be again traced out, it will be found that each bore is in an axis of a generally rectangularly parallellopipedal segment, representing each a one sixteenth section of the block, the eight of these in this half block being integrally connected in a one and a quarter turn helix containing the passageway. Thus there is created, by the simplest of machining operations, a one and a quarter turn helical coil of massive construction whose conductive elements and cooling fluid pas-

sageway are both adequate for the heaviest of loads.

The other half of the structure shown need not be described in detail since it is a mirror image duplicate of that described above.

Obviously, if only a single-chambered single coil is desired, only half the original block will be used, the slot 30 then representing one end wall and the terminal tube 34 being inserted into the bore 21. Also, it seems too obvious to need detailed description or illustration that the same general method of boring and slotting can be extended if desired to lengthen the coil by additional fractional or whole turns, while still keeping the advantage of needing only the simplest of machining operations, straight drilling and straight planing or sawing. Furthermore, as variously and incidentally noted above, the method herein disclosed makes it possible to make a water cooled coil for inductive or high frequency electric heating out of nonductile conductive material such as block carbon or graphite.

It may be desirable in some instances to make a coil of nonductile conductive material where it is not necessary to provide for the use of cooling fluid. In such case, the drilling operations may be all omitted except such as are necessary to form the chambers 10 and 11 and, if necessary, to provide for connecting terminal members such as 16 and 34.

Considering the right hand half only of the duplex article disclosed, this being the simplest unit constructible in accordance with the invention, it is to be noted that the slot 32 extends half way up from the bottom and also half way in from the right end of the cubical body about the chamber 11, and intersects the periphery of the body half way down the left side, all along the bottom, all up the right side, and half across the top face, thus extending through three quarters of the periphery of the body in its plane. Were the plane of the slot 31 tilted to the left, the slot 32 would cut more than three quarters of the circumference of the body. Evidently the outer shape of the body need not be rectangularly parallellopipedal, nor do the planes of the slots 31, 32 and 33, nor the axes of the bores 17, 19, etc. need to be mutually at exact right angles, for the application of the invention. These directions and the outer shape of the body may be variously skewed and modified without departing from the spirit of the invention or from the scope of the appended claims.

I claim:

1. The method of making an integral angularly helical electrically conductive member which method comprises steps of forming in a body of electrically conductive material and having a chamber therein, a plane slot intersecting the chamber and intersecting more than half the periphery of the body in the plane of the slot, forming in the body a second plane slot meeting and communicating with the first named slot at a relatively large angle thereto and communicating with the chamber, and forming in the body a third plane slot at a relatively large angle to each of the first named and second named slots and communicating with the first named slot and with the chamber, the three slots and the chamber being so disposed and proportioned that the substance of the body is thereby divided into integrally united segments in an angularly helically aligned sequence coiled about the chamber.

2. The method of making an integral angularly helical electrically conductive member which

method comprises steps of forming a chamber in a body of electrically conductive material, and forming three plane slots in the body all intersecting the chamber and no two slots being parallel or co-planar, the three slots and the chamber being so disposed and proportioned that the substance of the body is thereby divided into integrally united segments in an angularly helically aligned sequence coiled about the chamber.

3. The method of making an integral angularly helical electrically conductive member which method comprises steps of forming in a body of electrically conductive material and having a chamber therein, a plane slot intersecting the chamber and intersecting more than half the periphery of the body in the plane of the slot, forming in the body in the plane of the slot, and communicating with the first named slot at a relatively large angle thereto and communicating with the chamber, forming in the body a third plane slot at a relatively large angle to each of the first named and second named slots and communicating with the first named slot and with the chamber, the three slots and the chamber being so disposed and proportioned that the substance of the body is thereby divided into integrally united segments in an angularly helically aligned sequence coiled about the chamber, in combination with steps of forming in the successive members of the sequence of segments a straight bore in each segment by boring into the segment from one surface to intersect the bore in the preceding segment near one end thereof, and closing the aperture of each bore except the first and last in the surface from which it was bored, the successive bores forming a continuously communicating passageway along the angularly axial line of the angularly helical sequence of segments.

4. The method of making an integral angularly helical electrically conductive member which method comprises steps of forming a chamber in a body of electrically conductive material, forming three plane slots in the body all intersecting the chamber and no two slots being parallel or co-planar, the three slots and the chamber being so disposed and proportioned that the substance of the body is thereby divided into integrally united segments in an angularly helically aligned sequence coiled about the chamber, in combination with steps of forming in the successive members of the sequence of segments a straight bore in each segment by boring into the segment from one surface to intersect the bore in the preceding segment near one end thereof, and closing the aperture of each bore except the first and last in the surface from which it was bored, the successive bores forming a continuously communicating passageway along the angularly axial line of the angularly helical sequence of segments.

5. An integral angularly helical conductive member comprising a body of electrically conductive material having a chamber therein and formed with a plane slot therein intersecting the chamber and intersecting more than half the periphery of the body in the plane of the slot, and the body being formed with a second plane slot meeting and communicating with the first named slot at a relatively large angle thereto and communicating with the chamber, and the body being formed with a third plane slot at a relatively

large angle to each of the first named and second named slots and communicating with the first named slot and with the chamber, the three slots and the chamber being so disposed and proportioned that the substance of the body is thereby divided into integrally united segments in an angularly helically aligned sequence coiled about the chamber.

6. An integral angularly helical conductive member comprising a body of electrically conductive material having a chamber therein and formed with three plane slots in the body all intersecting the chamber and no two slots being parallel or co-planar, the three slots and the chamber being so disposed and proportioned that the substance of the body is thereby divided into integrally united segments in an angularly helically aligned sequence coiled about the chamber.

7. An integral angularly helical conductive member comprising a body of electrically conductive material having a chamber therein and formed with a plane slot therein intersecting the chamber and intersecting more than half the periphery of the body in the plane of the slot, and the body being formed with a second plane slot meeting and communicating with the first named slot at a relatively large angle thereto and communicating with the chamber, and the body being formed with a third plane slot at a relatively large angle to each of the first named and second named slots and communicating with the first named slot and with the chamber, the three slots and the chamber being so disposed and proportioned that the substance of the body is thereby divided into integrally united segments in an angularly helically aligned sequence coiled about the chamber, and each segment being formed with a straight bore therein intersecting the bore in the next adjacent segment near one end thereof, the successive bores forming a continuously communicating passageway along the angularly axial lines of the angularly helical sequence of segments.

8. An integral angularly helical conductive member comprising a body of electrically conductive material having a chamber therein and formed with three plane slots in the body all intersecting the chamber and no two slots being parallel or co-planar, the three slots and the chamber being so disposed and proportioned that the substance of the body is thereby divided into integrally united segments in an angularly helically aligned sequence coiled about the chamber, and each segment being formed with a straight bore therein intersecting the bore in the next adjacent segment near one end thereof, the successive bores forming a continuously communicating passageway along the angularly axial line of the angularly helical sequence of segments.
